UNITED STATES PATENT OFFICE.

HAROLD D. THOMAS AND WILLIAM H. ODLUM, OF CHICAGO, ILLINOIS, ASSIGNEES TO LINCOLN PRODUCTS COMPANY, OF CHICAGO, ILLINOIS, A CORPORATION OF DELAWARE.

BRACKET FOR SNUBBERS AND THE LIKE.

Application filed June 29, 1923. Serial No. 648,523.

To all whom it may concern:

Be it known that we, HAROLD D. THOMAS and WILLIAM H. ODLUM, both citizens of the United States, and both residing at Chicago, in the county of Cook and State of Illinois, have invented certain new and useful Improvements in Brackets for Snubbers and the like, of which the following is a specification.

10 This invention has to do with improvements in brackets for attaching the lower ends of the snubber straps to the axles of vehicles. The invention has reference particularly to improvements in a bracket for 15 attaching the lower end of the strap to a vehicle axle of I-beam cross section.

One of the objects of the invention is to provide a very simple form of bracket which can be readily attached to the flange of the 20 I-beam in a direct manner and by the simple application of a single tie bolt. Another object in this connection is to provide a bracket construction which will readily adapt itself to variations or inequalities in 25 the size of the flange, so that a single standard form of bracket construction can be used with different I-beam sizes.

Another object of the invention is to provide a construction of bracket which will readily adapt itself to irregularities or inequalities in the form of the axle without any tendency to bind or twist the through 30 bolt itself.

Other objects and uses of the invention 35 consist in the features of construction and combination of parts hereinafter described and claimed.

In the drawing:

40 Figure 1 shows a side view of a bracket embodying the features of the present invention as the same may be applied to the lower flange of an I-beam axle, the lower portion of the snubber strap being shown as attached to the bracket;

45 Fig. 2 is a bottom view corresponding to Fig. 1;

Fig. 3 is a vertical cross section taken on the line 3—3 of Fig. 2, looking in the direction of the arrows; and

50 Fig. 4 is an end view of the bracket arm together with a clip plate by means of which the lower end of the snubber strap is attached thereto.

For purposes of convenience, we have

herein illustrated the bracket of the present 55 invention as being applied to the lower flange 5 of an axle 6 of I-beam cross section. This is shown simply by way of illustration and without intending thereby to limit the application or usefulness of the invention, except as we may do so in the claims.

The bracket itself comprises the telescoping members 7 and 8. Each of these is of substantially semi-circular cross section; the member 7 having the side fingers 9 and 10 65 which lie against the bottom 6 of the flange 5, and the member 8 having the side fingers 11 and 12 which also lie against the bottom face of the flange 5, but are sufficiently separated to straddle the member 7. 70

The top surfaces of the fingers 9—10 and 11—12 are flat, as is evident from Figs. 1 and 3, so that they can ride evenly against the bottom surface of the axle flange 5.

The member 7 is provided with the upwardly extending hook finger 13, and the member 8 is provided with the upwardly extending hook member 14. These fingers are centrally placed on their respective bracket members, so that they engage the top edge 80 portions of the flange 5 at points centrally above the companion fingers 9—10 and 11—12 respectively. Consequently, each bracket member takes practically a three point support on the flange of the I-beam. 85

The bracket members are provided with through openings 15 and 16 respectively. The tie bolt 17 passes through these openings and draws the bracket members together. These openings are preferably of 90 sufficient size to allow of a certain amount of tilting of the bracket members with respect to the through bolt, or the openings may be tapered in form as clearly illustrated in Fig. 3. In either case the bracket members 95 are enabled to adjust themselves with respect to the through bolt so as to make a perfectly flat and even engagement with respect to the I-beam flange and without binding on the shank of the bolt. The bolt is provided with the bolt head 18 on one end, and the nut 19 on the other end permits the necessary pressure to be applied to draw the sections together.

The bracket member 8 is provided with an 105 outwardly reaching bracket arm 20, preferably as an integral portion thereof. The end of the bracket arm 20 is preferably

enlarged, as illustrated in Fig. 2 in particular, and its end surface 21 preferably lies at an angle with respect to the vertical, this angularity depending largely upon the 5 angle at which the snubber strap 22 is brought down to the bracket. In this connection, it is desirable to establish the slope of the surface 21 in such direction that the snubber strap 22 will lie against it without 10 having to bend the strap 22 sharply at the point where it comes against the surface 21.

A clamping plate 23 is set against the outside of the strap and is drawn to the bracket 20 by the tie bolts 24 and 25 respectively. Preferably, the head portion of the bracket and also the plate 23 are sufficiently large to pass the snubber strap between the bolts 24 and 25 as clearly shown in Fig. 4.

20 While we have herein shown and described only a single embodiment of the features of our present invention, still we do not intend to limit ourselves to the same, except as we may do so in the claims.

25 We claim:

1. The combination with a flange and the end portion of a snubber strap extending at an angle thereto, of a bracket therefor comprising a pair of bracket members, each 30 having a pair of horizontal separated fingers adapted to engage the under surface of the flange and each having an inwardly projecting hook finger in its upper portion adapted to engage the edge of the flange at 35 a point centrally above the two fingers aforesaid, the fingers of one bracket member being adapted to telescope between those of the other bracket member, there being a transversely extending through opening in 40 each bracket member, enlarged at its inner end, a through bolt extending through said openings to draw them together, a bracket arm extending outwardly from one bracket member and having at its outer end a clamping surface lying parallel to the direction of the snubber strap, 45 and means for clamping the snubber strap against said surface, substantially as described.

50 2. The combination with a flange and the end portion of a snubber strap, of a bracket therefor comprising a pair of bracket members, each having a pair of horizontal separated fingers adapted to engage the under 55 surface of the flange and each having an inwardly projecting hook finger in its upper portion adapted to engage the edge of the flange at a point centrally above the two

fingers aforesaid, the fingers of one bracket member being adapted to telescope between those of the other bracket member, there being a transversely extending through opening in each bracket member, enlarged at its inner end, a through bolt extending through said openings to draw them together, a bracket arm extending outwardly from one bracket member and having at its outer end a clamping surface, and means for clamping the snubber strap against said surface, substantially as described. 70

3. The combination with a flange and the end portion of a snubber strap extending at an angle thereto, of a bracket therefor comprising a pair of bracket members, each having a pair of horizontal separated fingers 75 adapted to engage the under surface of the flange and each having an inwardly projecting hook finger in its upper portion adapted to engage the edge of the flange at a point centrally above the two fingers aforesaid, the fingers of one bracket member being adapted to telescope between those of the other bracket member, there being a transversely extending through opening in each bracket member, a through bolt extending through said openings to draw them together, a bracket arm extending outwardly from one bracket member and having at its outer end a clamping surface lying parallel to the direction of the snubber strap, 80 and means for clamping the snubber strap against said surface, substantially as described. 85

4. The combination with a flange and the end portion of a snubber strap, of a bracket therefor comprising a pair of bracket members, each having a pair of horizontal separated fingers adapted to engage the under surface of the flange and each having an inwardly projecting hook finger in its upper portion adapted to engage the edge of the flange at a point centrally above the two fingers aforesaid, the fingers of the bracket member being adapted to telescope between those of the other bracket member, there being a transversely extending through opening in each bracket member, a through bolt extending through said openings to draw them together, a bracket arm extending outwardly from one bracket member and having at its outer end a clamping surface, and means for clamping the snubber strap against said surface, substantially as described. 90 95 100 105 110
